UNITED STATES PATENT OFFICE.

VIRGIL E. DUEMLER, OF MAPLEWOOD, AND GEORGE R. KOELN, OF ST. LOUIS, MISSOURI, ASSIGNORS, BY MESNE ASSIGNMENTS, TO ELECTROL, INC. OF MISSOURI, OF ST. LOUIS, MISSOURI, A CORPORATION OF MISSOURI.

THERMOSTATIC DEVICE.

Application filed January 19, 1925. Serial No. 3,406.

This invention relates to improvements in thermostatic devices, and consists in the novel construction hereinafter disclosed.

An object of the invention is to provide a thermostatic device that may be mounted in a heating element and arranged to close a circuit upon a predetermined minimum rise in temperature and to maintain the circuit closed during a rise in temperature 10 range, and to open the circuit upon a predetermined drop of temperature from any degree within the range of operation of the device.

Additional advantages of the construction will be apparent from the following detailed description thereof, taken in connection with the accompanying drawing, in which—

Fig. 1 is a front view with the cover removed.

Fig. 2 is a cross section on the line 2—2 of Fig. 1.

Fig. 3 is a cross section on the line 3—3 of Fig. 1.

In the embodiment of the invention illustrated in the drawing the invention is shown as comprising a case 1 having a front cover 2 and a cylindrical extension 3 running at right angles to the case constituting a housing for the thermostatic element of the device. Connected with the case 1 and surrounding the extension 3 is a threaded connection 4 adapted to thread into an opening in a wall 5 of the apparatus in which the device is to be mounted such, for instance, as the stack of a heating element or the wall of the combustion chamber of a heating element.

The device may be supported in place by jam nuts 6 operating against opposite sides of the wall 5 against washers 7, said jam nuts being threaded over the threaded portion of the connector 4.

A bi-metallic thermal plate 8 is connected to the end wall 9 of the casing 3, the plate 8 being connected preferably by a removable connection such as a bolt 10. The thermal element extends forwardly into the case 1, the forward end being free to move laterally under the influence of change of temperature surrounding the extension 3 of the case.

Extending transversely of the case 1 near the upper part thereof is an insulating member including three separated strips of insulating material 11, 12 and 13 respectively,

said insulating material being supported by the back wall of the case 1 by spaced bolts 14 passing through openings 15 in the back wall of the case. A bushing 16 serves to space said insulating element from the back wall of the case 1. The bolts 14 carry at 60 their forward ends nuts 17 between which and the forward edge of the bushing 16 are clamped the three strips of insulating material constituting the insulating element.

On the upper wall of the case 1 is a segmental insulating strip 18 through which the lower stems of binding posts 19 and 20, respectively, extend constituting means for connecting the device with opposite leads of an electric circuit.

Extending through the strips 11 and 13, respectively, in opposite directions and with their heads abutting against the separating strip 12 are bolts 21 and 22, the heads of said bolts being preferably made polygonal 70 and set in recesses formed in their respective retaining strips so that they will not turn.

A metallic connector plate 23 having an opening near its lower end fits over the shank of the bolt 21 and has its face against the face of the strip 11 and extends upwardly, and has an over-turned end with an opening therein that mounts over the lower end of the binding post 20 to which it is attached by a nut 24.

A similar connector plate 25 fits over the bolt 22 and abuts against the face of the strip 13 and is attached to the lower end of the binding post 19 by a nut 26. A contact plate 27 having an opening therein fits over the exterior of an internally threaded shank 28 of a nut 29, said nut 29 threading over the end of the bolt 21. The upper part of the plate 27 abuts against the face of the connector plate 23 and has an inwardly formed bead 30 for effecting contact with the connector plate 23, the contact plate 27 being held resiliently in contact with said plate 23 by a spring 31 interposed between the plate and the head of the nut 29 and mounted upon the exterior wall of the shank 28 of the nut.

The contact plate 27 carries near its lower end a pair of inwardly extending ears 32 and 33, the ear 32 having on its inner face an insulating strip 34 and the ear 33 having formed in connection therewith a contact member 35.

A second contact plate 36 is mounted on the shank 37 of a nut 38 and has a bead 39 abutting against the face of the plate 25, the arrangement for the mounting of the plate 36 being a duplicate of that for the plate 27. The plate 36 is of greater length than the plate 27 and extends downwardly to the lower part of the case 1 having a bifurcated end 40 that fits over the outer 10 end of the thermostatic element 8 and has inwardly extending ears 41 and 42 in substantial alignment with the ears 32 and 33 of the plate 27.

A U-shaped contact spring 43 is attached 15 at one end to the inner face of the ear 41 and extends exteriorly of the ear 42 and has a contact member 44.

The operation of the device is as follows: Upon a change in temperature surrounding 20 the portion 3 of the case the outer end of the thermostatic plate 8 is deflected laterally, until the contact element 44 makes contact with the contact element 35. This closes the circuit through the device. A continued 25 further movement of the end of the thermostatic plate moves both contact plates 27 and 36 laterally in the same direction, the ear 42 serving as an abutment for the free end of the spring 43 and the contact elements 44 and 35 remaining in contact. Upon 30 a change in temperature in reverse degree upon a slight retracting movement of the end of the thermostatic plate, the contact between the elements 35 and 44 is immediately broken, opening the circuit. A further change in temperature in the reverse direction carries both of the contact plates 27 and 36 toward normal position.

It is obvious therefore that the device may 40 be used either to effect the making and breaking of the circuit within a narrow range and under the influence of heat or cold, depending upon the arrangement of the thermostatic plate 8, and that so long 45 as the change in temperature continues in one direction the contact will be closed and will remain closed during a substantial range in temperature in the same direction. Upon 50 a slight reverse change the contact will be immediately broken and as long as the temperature moves in the reverse direction the circuit will remain open.

We are aware that the invention may be modified in certain particulars without departing from the spirit and scope thereof. 55 We therefore do not limit ourselves to unessential details, but what we claim and desire to secure by Letters Patent is:

1. A thermostatic device comprising a 60 case, a thermostatic plate supported rigid with one wall of said case, a pair of pivoted contact elements, means for insulating said elements from each other, operative connections between the free end of said thermostatic plate and one of said elements, and

operative connections between said contact elements whereby movement in one direction will effect electrical connection between the two and a continued movement in said direction maintain said connection under the influence of a substantial temperature range, and will break contact between said elements upon a reverse change in temperature within a narrow range.

2. In a device of the class described, an 75 insulating support, a pair of contact elements pivoted on said support, terminal posts for two wires of a circuit, connector plates between said terminal posts and said contact elements respectively, resilient means 80 for maintaining contact between said connectors and the respective contact elements, a thermostatic plate operatively connected with one of said elements, and contact points carried by said contact elements, respectively, normally out of contact with each other and requiring independent movement of one of said contact members to effect contact.

3. In a device of the class described, an 90 insulating support, a pair of contact elements pivoted on said support, terminal posts for two wires of a circuit, connector plates between said terminal posts and said contact elements respectively, resilient means 95 for maintaining contact between said connectors and the respective contact elements, a thermostatic plate operatively connected with one of said elements, contact points carried by said contact elements respectively, normally out of contact with each other and requiring independent movement of one of said contact members to effect contact, 100 and means for effecting an operative connection between said contact elements whereby continued movement in one direction will move both contact elements to maintain contact between said contact points.

4. In a device of the class described, a pivoted contact plate having electrical connection with one lead of an electric circuit, ears carried by said plate near its free end, one of said ears being provided with an insulating abutment and the other of said ears being provided with an electrical contact 110 point, a second contact plate, ears carried by said second contact plate within the space between the ears of said first named plate, a contact spring rigidly supported by one of said last named ears, the other of said last 115 named ears constituting an abutment for the free end thereof, and a thermostatic plate operatively connected to said last named contact plate for moving the same.

5. In a thermostatic device, a pair of contact members arranged for limited independent movement, a heat controlled device for moving one of said members, contact points arranged on said members respectively to effect electrical contact when one of 125 130

- said member is moved in one direction and to break contact when said member is moved in the opposite direction, and an insulated abutment for insulating said elements when moved in the opposite direction.
6. In a thermostatic device, a pair of contact members arranged for limited independent movement, a thermostatic plate for moving one of said members, a resilient connection for making electrical contact when one member is moved in one direction and to break contact when said member is moved in the opposite direction, a connection between the pair of contact members whereby one of said members is moved in one direction by the other member without making electrical contact, and means for connecting said contact members with separate leads of a circuit respectively.
7. In a thermostatic device, a pair of contact members arranged for limited independent movement, a flat elongated thermostatic plate having one end fixed and the other end engaging one of said members to move the same, a connection for making electric contact when one member is moved in one direction and to break contact when said member is moved in the opposite direction, an insulated connection between the contact members, and means for connecting said contact members with separate leads of a circuit respectively. 20 25 30
